US00D875814S

(12) **United States Design Patent** (10) **Patent No.:** **US D875,814 S**
(45) **Date of Patent:** **** Feb. 18, 2020**

(54) **SECURITY CAMERA**

(71) Applicant: **AMAZON TECHNOLOGIES, INC.**,
Seattle, WA (US)

(72) Inventors: **James Siminoff**, Pacific Palisades, CA
(US); **Mark Siminoff**, Mountain View,
CA (US); **Spiro Sacre**, Los Angeles,
CA (US); **Matthew J England**, Santa
Monica, CA (US); **Christopher Loew**,
Palo Alto, CA (US)

(73) Assignee: **Amazon Technologies, Inc.**, Seattle,
WA (US)

(**) Term: **15 Years**

(21) Appl. No.: **29/669,220**

(22) Filed: **Nov. 6, 2018**

Related U.S. Application Data

(63) Continuation of application No. 29/610,934, filed on
Jul. 17, 2017, now Pat. No. Des. 839,336.

(57) **CLAIM**

The ornamental design for a security camera, as shown and described.

DESCRIPTION

FIG. 1 is a front perspective view of a security camera according to the present design;

FIG. 2 is a front elevational view of the security camera of FIG. 1;

FIG. 3 is a rear elevational view of the security camera of FIG. 1;

FIG. 4 is a left-side elevational view of the security camera of FIG. 1;

FIG. 5 is a right-side elevational view of the security camera of FIG. 1;

FIG. 6 is a top plan view of the security camera of FIG. 1; and,

FIG. 7 is a bottom plan view of the security camera of FIG. 1.

The broken lines depict portions of the security camera in which the design is embodied that form no part of the claimed design.

1 Claim, 7 Drawing Sheets
